(57) **CLAIM**

An ornamental design for a laryngoscope as shown and described.

DESCRIPTION

FIG. 1 is an illustration of a front perspective view of a laryngoscope;

FIG. 2 is an illustration of a front elevation view thereof;

FIG. 3 is an illustration of a rear elevation view thereof;

FIG. 4 is an illustration of a right-side view of thereof;

FIG. 5 is an illustration of a left-side view thereof;

FIG. 6 is an illustration of a top view thereof; and,

FIG. 7 is an illustration of a bottom view thereof.

The broken lines shown as dashed lines are for the purpose of illustrating unclaimed structure, and form no part of the claimed design.

1 Claim, 5 Drawing Sheets
